(57) **CLAIM**

The ornamental design for a waste container, as shown and described.

DESCRIPTION

FIG. 1 is an isometric view of a waste container showing my new design;

FIG. 2 is an isometric view of the base of the container;

FIG. 3 is a top isometric view of the cover of the container;
FIG. 4 is a bottom isometric view of the cover of the container;

FIG. 5 is a rear elevation view of FIG. 1;

FIG. 6 is a front elevation view thereof;

FIG. 7 is a right side elevation view thereof; and,

FIG. 8 is a left side elevation view thereof.

The base and the cover are being shown separated in FIGS. 2, 3 and 4 for convenience of illustration.
